A. H. DE VOE.
TRIMMING MECHANISM FOR SEWING MACHINES.
APPLICATION FILED MAR. 27, 1917.

Patented Dec. 31, 1918.

UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TRIMMING MECHANISM FOR SEWING-MACHINES.

1,289,125.

Specification of Letters Patent. Patented Dec. 31, 1918.

Application filed March 27, 1917. Serial No. 157,609.

To all whom it may concern:

Be it known that I, ALBERT H. DE VOE, a citizen of the United States, residing at Westfield, in the county of Union and State 5 of New Jersey, have invented certain new and useful Improvements in Trimming Mechanisms for Sewing-Machines, of which the following is a specification, reference being had therein to the accompanying 10 drawings.

This invention relates to trimming mechanisms for sewing machines.

It has for its object the improvement of the efficiency of trimming mechanisms so 15 that they will stand up longer in service without resharpening of the blades. A further aim has been to simplify and compact the arrangement of a sewing machine equipped with a trimming mechanism.

20 The trimming mechanism comprises a ledger-blade adjustably mounted below the throat-plate and a movable blade sustained by a flexible carrier which is supported and actuated through a pivotal connection 25 with a rock-lever fulcrumed on the head of an overhanging arm on which is pivotally mounted a needle-operating lever that is operatively connected to the needle-bar and the rock-lever. The operative connections 30 mentioned include a link having a perforated arm constituting a take-up for the thread passing to the needle. A second link hinged at a point in rear of and slightly 35 below the overhanging arm is pivotally connected to the flexible blade-carrier and compels the movable blade thereon to reciprocate in a substantially perpendicular direction as it is actuated by the rock-lever.

40 The invention further consists in certain details of construction which will appear in the description of the invention embodied in the drawings, in which Figure 1 is a perspective view of the invention. Fig. 2 is a vertical section through the pivotal supporting and actuating connection of the 45 blade-carrier. Fig. 3 is a horizontal section through the vertical limb of the blade-carrier.

50 The invention is applicable to almost any type of stitch-forming mechanism. As shown it is embodied in a chain-stitch machine similar to that found in my pending application Serial No. 114,503, filed August 12, 1916. A needle 1 is reciprocated through 55 a hole 2 in the throat-plate 3 by a needle-

lever 4 pivoted at 5 in the overhanging arm 6 and connected by a link 8 to a clamp 9 suitably fixed to the needle-bar 10. The clamp 9 has a vertical lug 11 tapped to receive a stud-screw 12 by which it is pivotally connected to the lower end of a link 13 having a lateral arm 14 pierced to receive thread passing to the needle and forming a take-up for controlling the thread in a manner well known. The link 13 is connected 60 at its upper end to a stud-screw 12' tapped into one end of a rock-lever 15, the other end of which is fixed to a pin 16 pivotally supported in a bearing bracket 17 secured to the overhanging arm 6 in any suitable 65 manner. A collar 18 fastened to the pin 16 by the set-screw 19 constrains the rock-lever to move in a plane parallel with a vertical plane through the line of stitch-formation.

A pair of cutting blades are located in 70 advance and to one side of the needle. The lower or ledger-blade 20 is adjustably mounted beneath the throat-plate as shown and described in Patent to Grieb, No. 933,033, of August 31, 1909, a screw 21 80 affording means for adjusting it laterally. A second and movable blade 22, having a cutting edge 23 inclined to the horizontal surface of the throat-plate, is removably and adjustably secured by a set-screw 24 in a 85 suitably channeled lower end of a flexible blade-carrier 25 which is split as indicated at 25' to allow a firm grip on the blade. The blade-carrier has a vertical body-portion 90 which is arranged substantially in parallelism with the needle-bar and at its upper end is bent at substantially right angles to its body-portion as clearly shown in the drawings. In the end of the bent portion of the blade-carrier a split boss 25'' is 95 formed and by means of the screw 26 it may be clamped on a sleeve 27 drilled to receive the pivot-pin 28 having a head 28', a shoulder 29, and a threaded extremity 30 screwed into the rock-lever 15 and clamped 100 by a lock-nut 31. There is thus formed a pivotal supporting and actuating connection between the rock-lever 15 and the blade-carrier located in rear of the line in which the 105 needle reciprocates. Intermediate its ends the blade-carrier has a laterally extending pin 32 slidably embraced by the boss 33 on the end of a link or hinge 34 fastened by the screw 35 to the rod 36 which is slidably supported in the bearing bosses 37 and 38 110

sustained in rear of and slightly below the overhanging arm of the machine. A collar 39 adjustably secured on the rod 36 by the set-screw 40 is adapted to receive the thrust 5 of a compressed spring 41 coiled about the rod as it reacts against the fixed bearing boss 38.

The presser-foot 42 is of any suitable form and as shown is equipped with a hardened wear-plate 43 secured by screw 44, a slot 45 permitting adjustment so that it may be set against the movable blade. The throat-plate is also of old and well-known form and has serrations 46 on its upper 15 face for resisting rearward slip of the material being operated upon as it passes through the machine. A chute for the trimmed off material is shown at 47.

Features or principles underlying the invention, as it is at present understood, will 20 now be mentioned.

Owing to the construction and arrangement of the members 25, 34, 36 and 41 there 25 is a tendency to spring or buckle the flexible member 25 so as to incline the blade 22 relative to the line of feed, the portion of the blade nearest the operator's position extending toward the left. In this way the trimming mechanism has an action similar to 30 that of a pair of scissors the blades contacting at substantially the trimming point only. Thus a very efficient action of the cutting mechanism is secured and the blades have a self-sharpening action which enables 35 them to stand up in service for a considerable time without regrinding.

Slight lateral adjustment of the ledger-blade in either direction may be made without the necessity of separately adjusting the 40 movable blade because of the flexible character of the carrier together with the application of a constant spring pressure as above mentioned. To avoid too great or too small an angular relation between the cutting 45 edges of the blades and a consequent loss of efficiency and durability the carrier may be separately adjusted laterally by means of the split boss and screw formed on its upper end.

50 While the blade-carrier is flexible in a lateral direction it is stiffened to resist the vertically directed reaction of the cutting operation by a flange or rib 48, Fig. 3 formed integrally (or in any suitable manner) on 55 the front edge of the vertical leg of the blade-carrier.

By the flatwise arrangement of the blade-carrier, rock-lever and the link actuating the rock-lever and also by mounting the take-up 60 directly on the link actuating the rock-lever the mechanism is simplified and compacted.

Having thus set forth the nature of the invention, what I claim herein is:—

65 1. In a sewing machine, in combination, a needle-carrying bar, a needle-bar operating

lever and a link connecting said bar and operating lever, a ledger-blade, a movable blade coöperating therewith, a pivoted carrier for said movable blade, a take-up for controlling the needle-thread, common means 70 actuated by said needle-bar operating lever for operating said take-up and blade-carrier.

2. In a sewing machine having a needle and a needle-bar, a needle-bar operating lever, a link connecting said bar and said 75 operating lever, a lower blade, an upper movable blade coöperating therewith, a carrier for said movable blade, a rock-lever having a fixed fulcrum, a link connecting said rock-lever and needle-bar, a take-up operated by said last-named link for controlling the thread carried by the needle, a pivotal connection between said rock-lever and said 80 blade-carrier, and means for guiding the movable blade.

85 3. In a sewing machine, in combination, a needle, a needle-bar, a needle-operating lever, a link connecting said bar and operating lever, a ledger-blade, a movable blade coöperating therewith, a carrier for said movable blade, a rock-lever fulcrumed at one 90 end, a link connected to the other end of said rock-lever, a connection between said link and said needle-bar, a pivotal connection between said blade-carrier and said rock-lever 95 intermediate the ends of the rock-lever, a thread-controlling device actuated by said link, and means for guiding the movable blade in a substantially straight line.

4. In a sewing machine, in combination, 100 a needle, a needle-bar, a needle-operating lever, a link connecting said bar and operating lever, a ledger-blade, a movable blade coöperating therewith, a carrier for said movable blade, means operatively supporting 105 said blade-carrier, a take-up controlling the thread carried by the needle, and common means for actuating said take-up and blade-carrier.

5. In a trimmer for sewing machines, a 110 ledger-blade, a movable blade coöperating therewith, a needle carrying bar, a carrier pivoted intermediate its ends and holding at its lower end said movable blade, and means for sustaining and actuating said 115 carrier from its upper end, said means including a rock-lever movable in a plane parallel to the plane of the movable blade, a link connecting said rock-lever and needle-bar, said carrier of the movable blade being 120 pivoted to said rock-lever intermediate its connection with the link and its fulcrum.

6. In a trimmer for sewing machines having a needle-carrying bar and actuating mechanism therefor, in combination with a 125 ledger-blade, a movable blade in advance of said needle-bar, a carrier for said movable blade, and means for supporting and actuating said carrier including, a link pivoted in rear of said needle, a supporting and ac- 130

5 tuating rock-lever pivoted to the upper end of said carrier, a link connecting said rock-lever and needle-bar, said needle-bar having a longer stroke than said movable blade mounted on said carrier.

7. In a trimmer for sewing machines having a needle, suitable actuating mechanism therefor and a throat-plate, in combination, a ledger-blade having a cutting edge substantially flush with the throat-plate, a movable blade coöperating therewith and having a cutting edge inclined to the throat-plate, a flexible carrier for said movable blade arranged in a plane substantially parallel to a vertical plane through the line of stitch-formation, means connected to said blade-carrier intermediate its ends and in advance of the line of needle actuation for guiding the movable blade in a substantially perpendicular line, means connected to the upper portion of the blade-carrier in rear of the line of needle-actuation for supporting and actuating the carrier, and a spring pressing on the carrier at a point in advance of the line of needle actuation in a direction tending to flex the carrier toward the ledger-blade whereby the cutting edge of the movable blade may be moved downwardly at an angle across the cutting edge of the ledger-blade.

8. In a trimmer for sewing machines having a needle, suitable actuating mechanism therefor, and a throat-plate, in combination, an adjustable ledger-blade having a cutting edge substantially flush with the throat-plate, a movable blade coöperating therewith and having a cutting edge inclined to the horizontal, a flexible carrier for said movable blade arranged in a plane substan-

tially parallel to a vertical plane through the line of stitch-formation, means connected to said blade-carrier intermediate its ends and in advance of the line of needle-actuation for guiding the movable blade in a substantially perpendicular line, means 45 adjustably connected to the upper portion of the blade-carrier in rear of the line of needle-actuation for supporting and actuating the carrier, and a spring for pressing the means for guiding the carrier in a direction tending to flex the carrier toward the ledger-blade whereby the cutting edge of the movable blade may be operatively maintained at a small angle to the cutting edge 50 of the ledger-blade. 55

9. In a trimmer for sewing machines having a needle and suitable actuating mechanism therefor, a ledger-blade, a movable blade coöperating therewith, and a flexible carrier for said movable blade having a substantially vertical portion arranged in parallelism with and in advance of the needle, said flexible carrier also having an upper end portion arranged rearwardly of the vertical portion, means actuating and supporting said carrier and pivotally connected to the upper end portion thereof, means compelling the carrier to move in a substantially perpendicular direction, and means constantly pressing said flexible carrier side- 65 wise at a point remote from its pivotal actuating and supporting connection whereby the cutting edge of the movable blade may be made to assume a slight angular relation to the ledger-blade. 70 75

In testimony whereof, I have signed my name to this specification.

ALBERT H. DE VOE.
